CLAIM

The ornamental design for a display screen or portion thereof with a graphical user interface, as shown and described.

DESCRIPTION

The FIGURE is a front view of a display screen or portion thereof with a graphical user interface according to the new design.

The outermost rectangular broken line in the FIGURE illustrates a display screen or portion thereof and forms no part of the claimed design. The remaining broken lines represent elements of the graphical user interface that form no part of the claimed design.

1 Claim, 1 Drawing Sheet
